UNITED STATES PATENT OFFICE.

WILLIAM H. COLE, OF NEW YORK, N. Y.

PUMP.

1,198,110.

Specification of Letters Patent. Patented Sept. 12, 1916.

Application filed October 6, 1913. Serial No. 793,654.

To all whom it may concern:

Be it known that I, WILLIAM H. COLE, a citizen of the United States of America, residing in the borough of Brooklyn, county 5 of Kings, city and State of New York, have invented certain new and useful Improvements in Pumps, of which the following is a specification.

This invention relates to pumps, and aims 10 to provide certain improvements therein.

The invention is especially directed to an improved construction of pump for operating on air or other gases, it being particularly designed for use in connection with 15 gas engine starters operating by compressed air. For such purposes it is highly desirable to provide a pump of compact and simple construction which is capable of working at a pressure of from 150 to 300 pounds, and 20 which is durable in construction so that it can stand continuous operation without deterioration. It has heretofore been proposed to employ what are known as "impulse" pumps connected directly with the gas engine cylinder for the purpose of charging 25 the reservoir for starting purposes. Such impulse pumps, however, are not capable of efficient use except at pressures which are lower than those desirable for starting purposes. I hence provide a power driven 30 pump adapted to be coupled to the gas engine, the pump being adapted to positively compress the fluid in two stages by the use of a pair of pistons mounted in alinement, 35 and driven from a common crank. Fluid is drawn into the larger piston through a ring valve and is compressed through a gland valve into the smaller cylinder and thence is passed to the front of the latter for final compression.

Various points of the invention will be hereinafter more fully defined.

In the drawings I have shown in longitudinal section a complete pump embodying the invention.

Referring to the drawings, the driving shaft is indicated by the reference letter o^3 which carries a crank o^4 connected to the pitman o^5 . The shaft may be given a rotary motion in any suitable way as through a gear o^2 . The primary piston q is connected 50 and formed as a part of the piston rod p , the piston operating in a cylinder p' which

is connected to the frame o^6 by a flange p^2 , the flange being bolted to the frame, and the 55 cylinder being screwed into the flange. The bottom of the cylinder is provided with a head q^3 preferably screwing on the cylinder as shown, and in the piston head are formed a series of passages q' through which air is 60 admitted to the cylinder. The passages q' are controlled by a ring valve q^2 , the edges of which fit between the cylinder head and the end p^3 of the cylinder p' . The ring is thus permitted a sufficient play to open and 65 close satisfactorily by the suction and compression of the piston q . The charge of the cylinder p' is on the down stroke passed into the upper end of the smaller cylinder w through a gland valve s , the upper face of 70 which makes contact with a flange s' cast upon the cylinder head q^3 , while its downward movement is restrained by a ring s^6 screwing into an axial flange p^4 formed on the piston head. The ring s^6 is formed with 75 a series of passages s^5 for the passage of air which is compressed through the valve s . The valve s is constructed as a gland with a packing material s^3 compressed by a follower s^2 so as to make a tight joint around 80 the rod. The gland valve s is opened by the pressure above it or by friction on the rod when the piston q descends and is closed in the same manner when the piston q ascends.

The cylinder w is preferably secured to the piston head q^3 by screwing into the flange p^4 of the cylinder head. The secondary piston r is secured to the lower end of the piston rod p preferably by screwing it 90 onto the end as shown. The piston carries preferably a packing r^5 which is held in place by a cage r^2 screwing into the piston. The piston is provided with passages r' leading to a point above the cage, and the 95 latter is provided with passages r^6 leading to the valve seat r^7 controlled by a valve r^3 mounted upon a stem r^4 and preferably loaded with a spring r^8 adapted to normally maintain it upon its seat.

At the lower end of the cylinder w is mounted a valve casing t which is preferably provided with a plurality of valves t' t^2 which act as check valves through which the fluid under compression in the smaller 105 cylinder is passed. Suitable cages t^3 t^4 are

provided and the valves are preferably loaded with springs t^5 t^6 . For ease of construction and accessibility the cage t is preferably made in two parts t^7 t^8 screwed together as shown.

The pump is lubricated preferably by an oil cup x which is mounted upon a hood or casing x' , the top of the pitman rod being provided with a passage x^2 which permits oil to flow to the crank pin. Oil also drips by gravity into the several cylinders.

The operation will be apparent from the foregoing description. Upon rotation of the shaft o^3 both pistons are reciprocated. Upon the ascent of the larger piston air is drawn in around the ring valve q^2 which closes by its own weight or by compression, at the top of the stroke of the piston. Upon the descent of the larger piston air is compressed through the gland valve s into the upper end of the lower cylinder. Upon ascent of the smaller piston the air partially compressed above it passes into the lower part of the smaller cylinder through the check valve r^3 , and upon the subsequent descent of the smaller piston the air is forced under considerable pressure through the check valves t' t^2 into the reservoir or tank.

The pump thus constructed has been found to be extremely efficient and durable in practice. It operates successfully against pressures as high as 300 pounds, and is capable of rapidly filling the ordinary tank or reservoir used upon starting systems for gas engines. The air is compressed by positively applied power and the clearances may be made very small, thus avoiding the air cushions which are necessary to impulse pumps, and the loss of compression involved in such cushions. Furthermore, there is no rebound or chattering of the pump, and consequently no loss of power from this source.

While I have shown and described the preferred embodiment of the invention it will be understood that I do not wish to be limited thereto, as various changes may be

made therein without departing from the spirit of the invention.

What I claim is:—

1. The combination of a primary cylinder 50 and a secondary cylinder mounted in axial alinement, a pair of pistons therein, a piston rod common to said pistons, a shaft for driving said pistons, an intake valve leading to the primary cylinder, an exhaust valve directly between the primary cylinder and the secondary cylinder, a check valve in the secondary piston, and an exhaust valve in the secondary cylinder.

2. The combination of a primary cylinder 60 and a secondary cylinder mounted in axial alinement, an imperforate primary piston mounted in one cylinder, a shaft for driving the same, a piston rod connected to said primary piston, a secondary piston mounted upon said rod, an intake valve for the primary cylinder, an exhaust valve directly between the primary cylinder and the secondary cylinder, a check valve in the secondary piston, and a check valve leading from said secondary cylinder.

3. The combination of a primary cylinder and a secondary cylinder mounted in axial alinement, an imperforate primary piston mounted in one cylinder, a shaft for driving 75 the same, a piston rod connected to said primary piston, a secondary piston mounted upon said rod, an intake valve for the primary cylinder, an exhaust valve opening from the primary cylinder into the secondary cylinder, said exhaust valve constructed with a gland, a check valve in the secondary piston, and an exhaust valve in the secondary cylinder.

In witness whereof, I have hereunto signed my name in the presence of two subscribing witnesses.

WILLIAM H. COLE.
